CLAIM

The ornamental design for a electronic article surveillance (EAS) tag with swiveling lanyard attachment, as shown and described.

DESCRIPTION

FIG. 1 is a side perspective view showing the electronic article surveillance (EAS) tag with swiveling lanyard attachment of our new design with the right side being a mirror image thereof;

FIG. 2 is a top plan view, wherein the right side is a mirror image thereof;

FIG. 3 is a right side elevational view, the left side being a mirror image thereof;

FIG. 4 is a front, top perspective view thereof; and,

FIG. 5 is a rear, bottom perspective view thereof.
